(57) **CLAIM**

The ornamental design for the grit chip, as shown and described.

DESCRIPTION

FIG. 1 is a perspective top view of a grit chip of our new, original and ornamental design;

FIG. 2 is a perspective bottom view thereof;

FIG. 3 is a top view thereof;

FIG. 4 is a bottom view thereof;

FIG. 5 is a side view showing a curled edge thereof;

FIG. 6 is the opposite side view showing a curled edge thereof;

FIG. 7 is an end view showing an end of the chip across its width; and,

FIG. 8 is an opposite end view showing an end of the chip across its width.

The darker stippled shading represents shadows from the shape of the chip.
